UNITED STATES PATENT OFFICE.

PETER SISCO, OF CHICAGO, ILLINOIS.

DESIGN FOR AN IMAGE, STATUETTE, CONFIGURATION OF A BAR OF CANDY, OR SIMILAR ARTICLE OF MANUFACTURE.

54,783.

Specification for Design.

Patented Mar. 23, 1920.

Application filed June 18, 1919. Serial No. 305,191. Term of patent 7 years.

To all whom it may concern:

Be it known that I, PETER Sisco, a citizen of the United States, residing at the city of Chicago, in the county of Cook and State of Illinois, have invented a new, original, and ornamental Design for an Image, Statuette, Configuration of a Bar of Candy, or Similar Article of Manufacture, as shown in the accompanying drawing and described in the following specification.

showing my new design. Fig. 2 is a rear view of the said article showing my new design.

I claim:

The ornamental design for an image, statuette, configuration of a bar of candy, or similar article of manufacture as shown.

PETER SISCO.
